COLLAR DECAPPER APPLYING MACHINE

Robert Edwin Reardon, Camden, N.J.

Application April 27, 1946, Serial No. 665,535

2 Claims. (Cl. 29—33)

1

My invention relates to improvements in machines for forming and applying accessory devices to bottles or other containers and particularly relates to a machine for forming and applying an individual decapper to bottles and similar containers, especially those designed for closure by crown caps.

This application is a re-presentation in part of my prior application filed March 28, 1936, Ser. No. 71,481, on Collar Decappers and Forming of Same, which issued as Patent 2,183,588 on Collar Decappers, December 19, 1939.

The object of my invention is to provide a collar decapper applying machine having means for receiving a plurality of decapper blanks of thin sheet metal or equivalent material, which have been partially pre-formed for economy and facility of handling in such condition; feeding said blanks to a readily changeable shaping arbor and die therefor, designed to impart any desired final formation to fit the head and neck finish of the bottle or other container to which they are to be applied, including embossment of a label or advertising design if so desired; and then, after the final formation is imparted—in this case that of a collar—passing the finished decapper to means for momentarily intercepting the bottles or other containers as they pass on a chain conveyor adjacent to which my machine has been adjusted, and placing one of said decapper collars on each bottle or container as it passes along to the filling and crowning machines.

I attain my object by the mechanism illustrated in the accompanying drawings, in which:

Fig. 1 is a side elevation of the entire machine, with portions shown in vertical section and the standard cut away to shorten same in drawing.

Fig. 2 is a horizontal section on the line 2—2 of Fig. 1, prior to the action of the shaping die on a pre-formed blank and the shaping arbor.

Fig. 3 is a horizontal section on the line 2—2 of Fig. 1, showing the action of the shaping die on a blank and the shaping arbor.

Fig. 4 is a facial elevation of the shaping die, on line 4—4 of Fig. 2.

Fig. 5 is a horizontal section on line 5—5 of Fig. 1, showing the application of a fully formed decapping collar to a bottle.

Fig. 6 is a rear elevation of a pre-formed decapper blank.

Fig. 7 is a side elevation of a bottle head with a collar decapper applied thereto, fully formed from the pre-formed blank.

Fig. 8 is a rear elevation of a collar decapper as applied to a bottle.

2

Similar numerals indicate similar parts throughout the several views.

My machine may be embodied as shown, made mainly of suitable cast or wrought metal and designed to stand beside a chain conveyor which carries bottles or other containers to be filled and crowned. A base 1 supports a main standard 2 which may be of substantially I-beam shape, and forward of same on the base is erected a tubular lesser standard 3 that is attached to the main standard at its upper end by a bracket 4 extended from the said main standard. Slidably mounted upon said tubular lesser standard 3 and adjustable vertically on same to suit the height of a bottle conveyor, by means of a slide collar and a set screw 5, is a bracket 6 which terminally embraces the chain conveyor 7 by the upward extension of an end arm 8, adjustable by set screw 8A, which may act as a guide and back support for the bottles or other containers travelling on the chain conveyor. On bracket 6 opposite said end arm 8 is rotatably mounted a star wheel 9 with its arms extending over the chain conveyor 7 to intercept and engage a passing bottle or other container and rotate as it moves along, the end arm 8 co-operating to contactually center the container in and between the embracing arms of the star wheel 9 at one point of the rotation of same. The stem of star wheel 9 is mounted in bracket 6 and extends through its bearing to mount on its lower end a bevel gear wheel 10 which engages a train of gears 11 in which is included a sprocket wheel 12 from which a drive chain 13 extends to a source of motive power. Included in said gear train 11 is a hub-mounted horizontally rotating gear wheel 14 which has a squared central aperture traversing its axis of rotation. Said gear train 11 terminates adjacent the lesser standard 3 in the bracket 6 in a flat disk wheel 15 having a transversive aperture off center in its face which engages a pivot stud on the lower end of a driving bar 17 that extends upward therefrom to pivotally engage a vertically adjustable collar 18 which is slidably mounted on the shank 19 of the decapper applying mechanism, which shank 19 is tubular and slides vertically within the tubular lesser standard 3. The collar 18 is held in position upon the shank 19 by a set screw 20, which affords means of adjusting the decapper applying mechanism to suit the height of the bottles or other containers to which the decappers are to be applied, the eccentric movement of disk wheel 15, by means of bar 17, raising and lowering the applier from and into steady head contact with the bottles or other

containers passing on conveyor 7. The tubular shank 19 of the applying mechanism supports a head portion comprised of a bracket 21 which extends forwardly over the lower bracket 6 and carries the decapper applying means. A hub-mounted bevel gear wheel 22 rotates horizontally on said bracket 21 and has a square central aperture transversive of its rotative axis, similar to that in gear wheel 15 on bracket 6 which is immediately below said wheel 22 and in vertical axial alignment with same. Geared at right angle to said wheel 22 and pivoted on bracket 21 is a vertically rotative gear wheel 23 of larger diameter which has a flat face on which is pivoted, suitably off center, one end of a driving bar 24 the other end of which is pivoted to a horizontally reciprocative plunger 25, which moves to and fro in a runway formed in bracket 21 by rail bearings 26 and 27 as said gear wheel 23 rotates. The forward end 28 of said plunger 25 is vertically hollowed and spring hinged in the center of said hollow are two horizontally extendable arcuate face plates 28A, preferably of hard rubber or the like, which are designed to resiliently contact the finished decapper collar, without defacing same, and push it upon a bottle neck when the bottle is intercepted by the intercepting mechanism below, until the laterally resilient decapping collar snaps into place on the bottle, as shown in Figure 7. In the forwardly projected terminal of bracket 21, at the end of the upper bearing rail 26 of the applying plunger 25, is mounted invertedly a shanked cone 29, of hard rubber or the like, preferably, held in place by insertion of its shank in the bracket frame, that is designed to descend into the mouth of the bottle intercepted and steady it while the plunger 25 thrusts a collar decapper upon the bottle. Rearward of this steadyng cone 29 a tubular shaft 30 extends upward through the bracket frame, forming an opening in and above the runway of the applying plunger to permit a fully formed decapper collar to drop in front of the said applier when the latter is in receded position, or temporarily rest upon the top of said applier if it is in forward position at the moment. Partly housed in said tubular shaft 30 is a metal slide post 31 down which the full formed decapper collars may embracingly slide within the said shaft 30. Vertically above and in alignment with the container intercepting mechanism, a bracket 32 extends from the main standard 2 and the upper end of said slide post 31 is attached to one side of a trap opening 33 in the lower side of said bracket 32. Adjacent the opening 33 and rearward of same there is mounted in the frame of bracket 32 for horizontal rotation a bevel gear wheel 34 that is in axial alignment with the square holed gear wheels 15 and 22 in the container intercepting and collar applying mechanisms below it on vertically adjustable brackets 6 and 21, which slide on and in the tubular lesser standard 3. Structurally integral with said gear wheel 34, which is hub mounted, is a square drive shaft 34A which extends downward vertically and passes slidably through the squared apertures in said lower gear wheels 15 and 22, being thus adapted to be turned by rotation of the lower gear wheel 15 by drive chain 13 and so transmit motion to the upper gear wheel 22 as it passes through same and finally rotate the uppermost wheel 34 in which it is secured terminally, as by pin 35. Mounted on the bracket 32 so as to mesh diagonally in said bevel gear wheel 34 is a transmission shaft 36 that has gear wheel terminals

37 and 38 which engage said wheel 34 and a bevel gear 39 on the front face of a vertically rotative disk wheel 40 pivoted above and rearwardly of said wheel 34, the said disk wheel 40 having a sprocket wheel 41 mounted on its reverse side. The said wheel 40 is pivoted centrally opposite a runway 42 formed thereat in bracket 32 by bearing rails 43 and 44. In said runway 42 is detachably mounted for reciprocative movement therein a compound shaping die comprised of various hinged and otherwise assembled co-operative parts, as 46, 47, 48, 49, 50 and 51, in Figs. 1, 2, 3 and 4, and adapted to wrap a semi-formed decapper blank, as 52, around a detachably mounted shaping arbor 53, by contact therewith, said shaping arbor being fixed in the path of the shaping die travel by securing means, such as pin 54, and readily changeable for a differently shaped arbor if desired, as by withdrawal and replacement of said pin 54. A forked driving bar 55 pivotally and detachably engages the rear body of the compound die, 45, as by means of studs 56 at the fork ends engaging apertures in said body. The flat rearward end of said driving bar 55 is pivoted on the flat face of the sprocket wheel 41 on the reverse side of the disk wheel 40, suitably off the center of same. The shaping die 45 thus moves to and from the arbor 53 as the disk wheel 40 rotates, and both die and arbor may be readily removed and replaced if others of different shape are desired to give final form to decapper blanks to fit the neck and head finish of different bottles. In the lower bearing 44 of the shaper runway 42 there is located, suitably distant from the arbor 53, the exit opening 33 for fully formed decapper collars. Immediately before the arbor 53 the runway floor forms a stop ledge 57 on which the semi-formed decapper blank may drop to rest in front of arbor 53, through an overhead inlet opening 58 which is located above said stop ledge 57. On the shaper driving bar 55, beyond the radius of disk wheel 40, is pivoted the lower end of an agitator bar 59 the upper end of which is pivoted as at 60 on the shank of a feed drum 61 with a domed top that is vertically and rotatively movable in the funnel shaft 62 of funnel shaped upper feed hopper 63 that is adapted to receive semi-formed decapper blanks and direct them into vertical grooves, as 64, of suitable formation to receive blanks in desired position, that are formed on and in the circumference of said feed drum 61, between same and the inner wall of said funnel shaft 62, the bottom of which grooves are closed, except at one discharge port 65, by a collar 66 mounted upon said feed drum body below said grooves and supported as by pins 67, but held in the funnel shaft 62 as by screw head 68 in a wall slot in said shaft. This permits the collar 66 a limited vertical movement with the feed drum 61 but no rotative movement with it, as such lateral movement would block the discharge port 65. At suitable distance below said feed drum body, in the funnel shaft 62, a rack collar 69 is set within the shaft and secured to its wall as by screws 70, thus forming an encircling rack around the lower ungrooved portion 71 of the drum body. Above this rack 69 on the drum body is freely pivoted a pawl 73 that is adapted to engage the rack 69 except when the feed drum ascends into hopper 63 to the limit of its vertical movement in the funnel shaft by action of the agitator bar 59. Then the pawl clears engagement with the rack and drops into rack teeth 75 more vertically below its pivotal point. Thus

when the feed drum descends by downward movement of the agitator bar 59 the new tooth engagement of pawl 73 with the rack operates to rotate the drum a space laterally, to both induce entrance of further blanks into the drum grooves from the funnel hopper 63 above and also move another vertical chute towards the discharge port 65. From the sprocket wheel 41 on the reverse of wheel disk 40 a drive chain ascends diagonally to the driving sprocket 75 of a sprocket wheel 76 that is pivoted at the top of main standard 2, adjacent the funnel hopper edge. This wheel 76 on its main sprocket carries a conveyor chain of linked segments, 77, that passes down the inner side of main standard 2 and around a suitable sprocket wheel 78 that is pivoted on the main standard adjacent its base, thence ascending along the rear face of the standard through a lower hopper 79—preferably usable for feeding blanks because most accessible, that is mounted on the standard 2 rear face and designed to feed its contents against the ascending conveyor chain 77, the linked segments of which are designed to engage decapper blanks in desired position and lift them to the upper funnel feed hopper 63, discharging them into same as the chain links invert in going over the sprocket wheel 75 adjacent the edge of said funnel hopper.

The operation of my decapper forming and applying machine as shown is effected as follows: First it is assumed that the machine is set up beside a chain conveyor for bottles and its connection therewith established by adjustment of brackets 6 and 21 to engage said conveyor and suit the height of the bottles used, the latter adjustment providing that the steady cone on bracket 21 will have enough rise and fall to enter and lift clear of the bottle mouths. Vertical adjustment of the brackets 6 and 21 is, of course, effected through their slidable mounting on and in the lesser standard 3 and the collar 18 and use of set screws 9 and 20. Then, preferably, the lower hopper 79 is filled with semi-formed decapper blanks—the upper hopper, not being so accessible for feeding but usable in emergency, normally functioning as a feeding reservoir of blanks passing to feed channels. The ascending conveyor chain 77 then passing upward on the inner wall of said lower hopper 79 engages a succession of decapper blanks in its linked segments and carries them up to the top of main standard 2, where the conveyor chain inverts its linked segments as it passes over the sprocket wheel 75 at the edge of upper hopper 63 and thus dumps the carried blanks into said hopper, one after the other, in the best position to facilitate their descent down the funnel-like wall of said upper hopper to the shaft 62 in same and the top of feed drum 61. There it either immediately enters one of the vertical grooves or slideways of the drum, as 64, or awaits proper entrance thereto alone or as one of an accumulation of blanks thereat, through the rise and rotative fall of said feed drum in the funnel shaft by operation of the mechanism below same: the agitator bar 59; driving bar 55; disk wheel 40; pawl 73; and rack collar 69. The decapper blank, as 80, having entered and descended to the bottom of one of said slide grooves, as 64, awaits rotation of that groove to the discharge port 65, where it slides down a discharging slideway 81; dives headfirst into an opposed opening or trip hole 82 in the frame of bracket 32 at that point which is suitably smaller than the blank body, so that the body weight causes the blank to swing around, pivoted on the trip hole edge, and drop downward

through the opening 58 above the stop ledge 57, to come to rest on said ledge in front of arbor 53 in proper position for shaping die action. The shaping die 45 then advances against the decapper blank by operation of drive bar 55 and its eccentric pivoting on wheel 40, and pushes the blank against arbor 53. Contact with arbor stops the central die member 47 and causes wings 48 and 49 of the die to converge under the advancing pressure of the die body 50 on them through spring plate 51, as the die body slides along the shank of the retarded central member 47, which abuts the blank and arbor, and the wings 48 and 49 press the blank sides forward and around the shaping arbor. Then in the withdrawal of the shaping die from the arbor the central member 47 of the die is static, and the wings 48 and 49 have no rear pressure upon them other than that exerted by the weak plate springs 51A and are diverged largely by the wedging effect of the arbor curvature upon their outer ends, thus pulling the fully formed blank off the arbor by engagement of the wing recesses with the ears 83 now extending laterally from the fully formed collar decapper. This engagement of the wings of the shaping die with the ears of the formed collar pulls the collar back from the arbor to a point where the wings release it above the exit well 33, by central die member 47 butting at rear end against a stud 47A while the shaping die body recedes farther. Then the formed collar, embracive of the slide post 31 in said exit well 33, slides down, to come to rest upon the top of the applying plunger 24—and drop off same as it recedes—or land immediately in front of said plunger if it is already receded sufficiently. The next forward movement of the applying plunger 24 then pushes fully formed collar decapper onto the neck and head finish of the bottle travelling on chain conveyor 7, which has at that moment reached the peak of its interception on said conveyor by the arms of star wheel 9 and the backing offered by the end arm 8 of bracket 6. The bottle, with collar decapper duly applied to it, then continues on its way to filling and capping operations—and the action is repeated.

While one preferable embodiment of my invention is illustrated and described herein, it is obvious that various embodiments and adaptations of it are practicable without departure from the spirit of the invention.

I claim:

1. A machine for applying decappers to bottles, wherein the decappers are preshaped as to their fundamental structure but require final curvature shaping to conform to the individual shape of a particular bottle neck so that the decappers conform to, extend around, and grip the neck to a greater extent than 180 degrees, said machine comprising; a feed for preshaped decappers; a detachable arbor of a shape corresponding to the individual shape of the particular bottle neck to which the decapper is to be applied; means for transferring decappers from said feed to said arbor and conforming the same thereto for obtaining the final curvature, and means for transferring said final contoured decappers from said arbor to a bottle neck and for applying the same thereto.
2. A machine for applying decappers to bottles, wherein the decappers are preshaped as to their fundamental structure but require final curvature shaping to conform to the individual shape of a particular bottle neck so that the decappers conform to, extend around, and grip

the neck to a greater extent than 180 degrees, said machine comprising; a feed for preshaped decappers; a detachable arbor of a shape corresponding to the individual shape of the particular bottle neck to which the decapper is to be applied, said arbor being less in diameter than said bottle neck; means for transferring decappers from said feed to said arbor and conforming the same thereto for obtaining the final curvature, and means for transferring said final contoured decappers from said arbor to a bottle neck and for applying the same thereto.
